INKING ARRANGEMENT FOR PRINTING MACHINES

Leslie Neville Peckham, Uxbridge, England, assignor to Bell Punch Company Limited, London, England, a British company

Application November 1, 1938, Serial No. 238,141
In Great Britain November 4, 1937

5 Claims. (Cl. 101—366)

This invention relates to inking devices for printing machines and more particularly to inking devices for machines for printing and issuing tickets, vouchers and the like.

5 The invention comprises the combination of an ink reservoir, a pad of ink-absorbent material which can be arranged in contact with a part serving to communicate ink to the printing surfaces in the printing machine, and means for 0 conveying ink from the reservoir to the said pad.

Preferably the reservoir, pad and ink conveying means are constructed in the form of a unit adapted to be removably positioned in the printing machine.

One manner of carrying the invention into effect is shown by way of example in the accompanying drawings in which

Fig. 1 is a perspective view showing the complete inker unit.

Fig. 2 is a part sectional side elevation to a smaller scale than that of Fig. 1 showing the unit in position in the printing machine, only those parts of the said machine which are necessary 5 for the understanding of the invention being shown.

Fig. 3 is a detail view showing the plunger and the actuating means therefor.

Referring to the drawings the inker is constructed in the form of a self-contained unit which can be removably located in the printing machine. As shown the unit comprises a body part 10 provided with a finger piece 11 for enabling the unit to be withdrawn from or inserted into the printing machine, the body part being supported on a pair of opposed guide rails 12 and being held in its correct position by the engagement of a spring-urged plunger 13 in a hole (not shown) in a side plate of the machine. The plunger 13 is arranged to be moved against the action of its spring 21 by means of a trigger-shaped lever 14 pivoted at 22 on the finger piece 11 and when it is desired to remove the inker unit from the machine the operator inserts a finger in the aperture in the finger piece and presses the trigger 14 to withdraw the plunger 13 from the hole in the sideplate whereupon the inker can be withdrawn from the machine along the guide rails 12.

As shown in Fig. 2 the body part 10 is formed with a hollow portion constituting a reservoir 15 for ink. Also the body part carries an ink-absorbent pad 16 the outer end of which projects beyond the body part and is subjected to the influence of a blade spring 17 serving to press the

end of the pad in a downward direction while the inner end of the pad is arranged to lie across the upper end of a conduit 18 communicating at its lower end with a cylindrical shaped chamber 19 which is in communication with the reservoir 15 via a conduit 20. Mounted to slide in the cylindrical chamber 19 is a plunger 23, the latter being formed with a circumferential groove 24 in which engages a projection 25 (Fig. 3) at the lower end of a rod 26 rotatable about its longitudinal axis in the body part 10. The rod 26 is provided at its upper end with a block 27 having a pin 28 which, when the inker unit is located in the printing machine, engages a snail cam 29 in the said machine, the rod 26 being urged in a direction to hold the pin 28 in engagement with the cam 29 and the plunger 23 at the rear end of the chamber 19 as shown in Fig. 2, by a coil spring 30 bearing on the block 27 and arranged around the upper end of the rod 26. The cam 29, having a fall 31, is secured on a rotatable spindle 32 mounted in the printing machine, the spindle 32 also carrying a toothed wheel 33 engageable by a spring urged pawl 34 mounted on a longitudinally movable bar 35 carrying at its upper end a push button 36. The push button 36 is arranged through the intermediary of the bar 35 to initiate the operation of the printing machine but as the mechanism for effecting this forms no part of the present invention it will not be further described. Each actuation of the button 36 causes the rotation of the toothed wheel 33 through one tooth and the cam 29 is accordingly rotated intermittently in a clockwise direction as viewed in Fig. 2 during the use of the machine to issue tickets.

Also when the inker unit is located in its correct position in the printing machine the projecting end of the pad 16 is arranged to bear against a metal roller 37 rotatably mounted in the printing machine, the said roller being positively driven from any convenient moving part in the printing machine and the pad being held against the roller by the blade spring 17. The metal roller 37 is also engaged by a rubber roller 38 serving to convey ink from the metal roller to the printing surfaces on the printing drum 39, the rubber roller 38 being carried in a pivotal frame 40 acted upon by a spring 41 serving to hold the rubber roller in contact with the metal roller and the printing surfaces.

The chamber 19 in which the plunger 23 operates is arranged at one side of the longitudinal centre line of the body part 10 near the rear end of the latter and the reservoir 15 ex-

tends alongside the said chamber on the other side of the centre line, this limb of the reservoir being provided with a screw plug 42 for enabling the reservoir to be replenished and the plug being provided with the usual vent hole.

5 The operation of the arrangement above described is as follows:

Assume at the time of commencing to use the machine that the parts of the mechanism occupy the positions shown in Fig. 2 with the pin 28 in the position indicated in full lines at the base of the fall 31 and the plunger 23 at the rear end of the chamber 19. Under these conditions ink will be present in the other end of 10 the chamber 19 to the level shown. Actuation of the button 36 to effect the issue of tickets will now cause the cam 29 to be rotated to rotate the rod 26 in a direction to move the plunger 23 towards the front end of the chamber 19, 15 continued movement of the plunger after it has closed the conduit 20 then serving to force ink into the pad 16. Movement of the plunger in a forward direction continues until the pin 28 occupies the position shown in dotted lines in 20 Fig. 2 and in full lines in Fig. 1 after which, 25 further rotation of the cam 29 permits the pin to be moved down the fall 31 so as to be restored to the dotted line position of Fig. 1 under the action of the spring 30. During this movement 30 the plunger 23 is returned to the rear end of the chamber 19 to permit ink to flow into the front end of the chamber and hence the parts of the inker mechanism are now restored to their initial positions shown in Fig. 2 ready for a further sequence of operations. Thus the pad 16 35 is charged with a quantity of ink once for each rotation of the cam 29.

Ink is picked up from the impregnated pad 16 by the positively driven metal roller 37 which 40 conveys it to the rubber roller 38 arranged for contact with the printing surfaces and in this way a film of ink is continuously conveyed to the printing surfaces so long as printing is being effected.

45 By this invention I am able to provide a simple and convenient form of inking device, intended more particularly for a ticket printing and issuing machine, which supplies ink to the printing surface in a very satisfactory manner.

50 The invention is not limited to the example described as subordinate details of construction may be varied to suit different requirements. For example the movement of the plunger 23 may be derived from any other convenient moving part in the printing machine.

Having now particularly described and ascertained the nature of my said invention and in what manner the same is to be performed, I declare that what I claim is:

1. In combination, an inking device comprising an absorbent ink-applying member and an ink pump arranged to supply ink to said absorbent member, means for guiding said inking device for sliding movements towards and away from an operative ink-applying position, means for latching said inking device in said position, and means for driving said pump, said means becoming operatively associated with the pump when the inking device is moved to its operative position. 5

2. In combination, an inking device comprising an absorbent ink-applying member and an ink pump arranged to supply ink to said absorbent member, means for guiding said inking device for sliding movements toward and away from an operative ink-applying position, means for latching said inking device in said position, and means for driving said pump, said driving means comprising a cam and a follower, the latter serving to drive the pump, said cam and follower being arranged to become operatively associated when the inking device is moved to its operative position. 10

3. In combination, a cyclically operating printing device, an inking device therein comprising an absorbent ink-applying member and a cyclically operating ink pump arranged to supply ink to said absorbent member, and ratchet means for driving said pump. 15

4. In combination, a cyclically operating printing device, an inking device therein comprising an absorbent ink-applying member and a cyclically operating ink pump arranged to supply ink to said absorbent member, and ratchet means for driving said pump through a single pumping cycle during a plurality of cycles of operation of the printing device. 20

5. In combination, an inking device comprising an absorbent ink-applying member, an ink reservoir, said member being located above said reservoir out of contact with ink therein, a conduit terminating at the under side of said member, and means receiving ink from the reservoir for forcing ink under pressure into said member through said conduit, and devices for driving said forcing means, said arrangement of parts providing flow of ink to said member against gravity only under the action of said forcing means. 25

LESLIE NEVILLE PECKHAM.
